CARTON

Paul Edward Schrell, Brooklyn, N. Y., assignor
to N. D. Q. Specialty Corporation, Brooklyn,
N. Y., a corporation of New York

Application March 22, 1939, Serial No. 263,492

2 Claims. (Cl. 229—28)

This invention relates to a folding carton and blank therefor and has special reference to a combination display container which combines both a box or outer container and cushion partition, the whole being made from a one piece cardboard blank.

One important object of the invention is to provide a carton of this class wherein the entire contents of the container is visible and wherein the box may be covered by a transparent cover which will protect the contents from dust, dirt and deterioration through evaporation.

A second important object of the invention is to provide a carton of this character having cushioned portions which support and protect fragile articles from breakage, the container being especially adapted to hold glass ornaments, chocolate covered confections, hollow chocolate and the like.

A third important object of the invention is to make this container from a single cardboard blank whereby to lessen expense of assembling several blanks, the entire container being formed by folding the parts into position and there securing them without the use of adhesives or the like.

With the above and other objects in view the invention consists in general of certain novel details of construction and combinations of parts hereinafter fully described, illustrated in the accompanying drawings, and particularly pointed out in the appended claims.

In the accompanying drawings, like characters of reference indicate like parts in the several views, and:

Figure 1 is a plan view of the blank from which this container is made.

Figure 2 is a top plan view of the container as formed from the blank shown in Figure 1.

Figure 3 is a longitudinal section on the line 3—3 of Figure 2 and showing the molded partitions.

Figure 4 is a transverse section of the line 4—4 of Figure 2 and particularly showing the manner of forming the middle rib and a face of one of the transverse partitions.

Figure 5 is a section, on an enlarged scale, on the line 5—5 of Figure 3, the section being fragmentary and showing merely the locking arrangement by which the blank is held to form the completed container.

Figure 6 is an enlarged detail bottom view of the interlocking means at each end of the container.

Figure 7 is a perspective view of the complete container.

In the embodiment of the invention as herein disclosed the blank consists of a rectangular body portion 10 having relatively long sides and relatively short ends and to the body portion 10 are connected bottom portions 11, the bottom portions being defined from the body portions by weakened or fold line 12 extending from end to end of the body portions. Each of these bottom portions is of general rectangular form but the outer corners thereof are rounded as at 13. To the edges of the portions 11 which are parallel to the fold line 12 are connected central rib portions 14 which are defined from the portions 11 by 15 weakened or fold lines 15.

Body portion 10 consists of a central part 16 and side parts 17. These parts 16 and 17 are defined from each other by a series of spaced slits 18 so that each series of slits forms a weakened or fold line enabling the side portions to be readily folded into position at right angles to the central portion 16. The slits at one side are arranged opposite the slits on the other side of the central portion and thus form spaced pairs. The slits of each pair have their ends connected by weakened or fold lines 19 so that the parts 17 are connected by transverse top portions 20. The portions between each pair of the side slits 18 and the pair of fold lines 19 constitute transverse partition 30 forming portions which are separated centrally between the fold lines 19 by crenelated slits 21 having opposed V-notches 22 formed in their separated edges at the middle portion thereof.

At each end of the body portion 10 there is provided a pair of end flap members 23 which are aligned with the side parts 17 and are defined therefrom by a fold or weakened line 24. At each end of the central portion 16 of the body 10 there is provided an end wall 25 which is defined from the portion 10 by a fold line 26. The portion 25 is separated from the portion 23 at each end by slits 27. Connected to that edge of the portion 25 which is parallel to the fold line 26 is a bottom flap portion 28 which is defined from the respective portion 25 by a weakened or fold line 29. Each fold line 29 is provided at its center with a slit 30 extending longitudinally on the fold line and on each portion 28 is a slit 31 parallel to the slit 30 and connected to the slit 30 by a transverse slit 32. Thus there is formed an H-locking slit in each end portion. Each of the portions 14 has at its ends a T-shaped member 33 which, as will be seen hereafter, engages in the H-shaped locking slit at the respective ends. 35

Furthermore, the outer or free edge of each portion 14 is provided with a series of spaced notches 34 aligned with the fold lines 19.

In setting up the device the blank may be laid 5 on a flat surface and then the parts 17 are bent up at right angles to the part 16 to form the longitudinal sides of the carton. After this the bottom portions 11 are bent over on the fold lines 12 to lie in a plane parallel with the portion 16 10 and the central rib portions 14 are bent on the fold line 15 to extend toward the portion 16 and contact with the transverse portion 20. Prior to this, however, the transverse partition portions 15 with their crenelated edges are bent substantially at right angles to the portion 20 so that the notches 22 and the notches 34 may interengage 15 and hold these parts in position. Next the parts 25 and 23 are bent on their fold lines so that the parts 25 lie outside of the part 23. Finally, the 20 end tabs 28 are bent at right angles to the portion 25 and tucked in so that one side of the T-shaped portion 33 can engage in the H-slot in the middle of the end portion.

When this is done a carton is provided with 25 side walls between which is a central wall or rib and said carton also is provided with yieldable transverse walls having crenelated lower edges so that articles placed in the compartment thus formed are supported against breakage by the 30 free crenelated edges of the transverse walls, it being understood that the slots 34 permit a certain amount of yielding of these walls.

Preferably the cover of this carton is made of 35 some transparent material such as Cellophane or Sylphrap adhesively secured to the sides and end parts of the carton or such carton may be entirely wrapped in material of this character.

It will now be seen that the carton is formed 40 from a single piece of cardboard or other like material and that there is substantially little waste in the cutting of the blank forming the device. It will also be seen that the device is very readily assembled and requires no adhesive for holding the parts together and, when so assembled, 45 forms a rugged and substantial carton. Finally, by means of the crenelated edges and movable transverse walls very delicate material may be supported in the carton without danger of fracture or other injury.

What is claimed, is:

1. A carton formed from a single blank of suitable cardboard-like material cut and scored to form a bottom, sides and ends, the bottom being scored to fold lengthwise to form a longitudinal partition, integral portions connecting the sides to form transverse partitions interlocking with the longitudinal partition to provide a series of individual compartments, each of said transverse partitions comprising a top member and a 10 pair of parallel depending walls integrally connected to the top member, said central and transverse partitions having co-acting notches with the notches of the central partition being wider than the thickness of the central partition thereby permitting yielding movement of said central partition. 15

2. A carton blank comprising a body portion of rectangular form having a central part forming portion adapted to constitute transverse top and 20 partition wall members, each of the parts forming the partition wall members consisting of a pair of wall portions divided by a crenelated slit and having a fold line at the opposite edge from the slit, each of said transverse walls forming portions having a central notch on the crenelated side, said body portion having side forming portions defined from the transverse wall portion by aligned slits, bottom portions connected to the outer edges of said side portions and defined therefrom by fold lines, central rib forming portions connected to the outer edges of the bottom forming portions and defined therefrom by fold line, said central rib forming portions being provided at their outer edges with pairs of spaced 25 notches and at their ends with substantially T-shaped lock engaging means, end portions projecting from the ends of said central portion and defined therefrom by fold lines, locking tabs projecting from the outer edges of the end portions 40 and defined therefrom by fold lines, H-shaped slits formed centrally on said flaps, and flaps extending from the side portions and defined therefrom by fold lines, and means on the end portion to engage said T-shaped locking portions. 45

PAUL EDWARD SCIRELL.
